UNITED STATES PATENT OFFICE.

THOMAS HILL, OF JERSEY CITY, NEW JERSEY.

BUILDING STRUCTURE.

1,258,410.

Specification of Letters Patent.

Patented Mar. 5, 1918.

Application filed May 29, 1916. Serial No. 100,561.

To all whom it may concern:

Be it known that I, THOMAS HILL, a citizen of the United States, and a resident of Jersey City, in the county of Hudson and State of New Jersey, have invented certain new and useful Improvements in Building Structures, of which the following is a specification.

The invention pertains more particularly to a novel structure for domes or towers of buildings, and in accordance with my invention I provide a superposed dome casting of special structural features adapted to receive the upper ends of rolled structural beams which will constitute the skeleton for the dome.

My invention has for its purpose to afford means whereby a dome may be quickly and with the minimum labor and expense erected and which shall at the same time be composed of parts of great durability and fewness in number.

The central top casting forming the superposed cap or center of the dome of my invention is an integral casting affording sockets for the upper ends of the rolled beams, said beams being riveted within said sockets, and preferably the sockets are so constructed that they afford bearing surfaces for the lateral flanges of the beams as well as for the lower and upper sides of the ends thereof. The dome caps of my invention not only afford sockets for the ends of the rolled beams constituting the skeleton frame for the dome, but also provide intermediate said sockets certain recesses which admit of the ends of the beams being securely riveted within the sockets, external fish plates and their attachments being omitted.

This invention is intended for use in tall buildings having structural steel frames of the rolled beam type, and therefore the features constituting my invention are of special character, strength, size and durability. I also with the use of my invention avoid complexity of parts and produce a structure which is comparatively simple but of great utility and durability.

The invention will be fully understood from the detailed description hereinafter

presented, reference being had to the accompanying drawings, in which:

Figure 1 is a vertical transverse section through the upper portion of a dome structure embodying my invention, the side beams being partly broken away; 55

Fig. 2 is a horizontal section, partly broken away, through the same, taken on the dotted line 2-2 of Fig. 1; 60

Fig. 3 is a like section, partly broken away, of the same taken on the dotted line 3-3 of Fig. 1;

Fig. 4 is a vertical section through a modified construction of dome cap, the modification residing in having the upper ornamental portion of the cap made separately from the body of the cap and fastened thereto, this modified construction being intended for use only in caps of great weight and 70 then as a convenience in the casting of the same; 65

Fig. 5 is a detached perspective view of the dome cap illustrated in Figs. 1, 2 and 3;

Fig. 6 is a top plan view, partly broken 75 away and partly in section, of the means provided for connecting the side beams of the dome and receiving the lower end of a securing rod extending down through the cap, the sectional portion of Fig. 6 being 80 taken on the dotted line 6-6 of Fig. 1;

Fig. 7 is a sectional view through a portion of a building structure employing several of the dome caps, the section being shown through the caps and the beams being 85 partly broken away; Fig. 7 shows one end of the structure with a dome cap thereon, and an intermediate cap, and the structure may be continued by the addition of further caps and beams; 90

Fig. 8 is a sectional view, partly broken away, through a dome structure employing a modified form of dome cap for the upper ends of the side beams, and

Fig. 9 is a horizontal section, on a larger 95 scale, through the same, taken on the dotted line 9-9 of Fig. 8.

In the drawings, referring to Figs. 1, 2, 3, 5 and 6, 15 designates the dome cap, 16 rolled beams secured at their upper ends 100 within said cap and constituting the sides of the dome, 17 adjustable stay rods con-

necting the beams 16 at a suitable distance below said cap, 18 a headed rod extending down through the cap 15 and through an opening in a disk 19 to which the inner ends 5 of the rods 17 are secured, and 20 a nut on the lower threaded end of said rod or bolt 18 and adapted to be screwed against the lower face of the disk 19 for securing the proper tension. The rods 17 are equipped 10 with turn-buckles 21, and hence are adjustable longitudinally, and said rods have on their outer ends pivoted plates 22 which engage the facing sides of the beams 16 and are flanged at their vertical edges to engage 15 the opposite edges of the inner flanges of said beams. The plates 22 will be secured by rivets to the facing flanges of the beams 16.

The essential portion of my invention resides in the provision of the dome cap 15 and rolled beams 16, and while my invention is not in every way limited to the beam 16 being of I-shape in cross-section, I prefer the use of I-beams and my dome cap 15 25 has been constructed accordingly.

The dome cap 15 is preferably in one integral casting, and its essential portion will always be in one integral casting, it being my purpose to secure great strength with 30 fewness of structural parts. The dome cap 15 may have an ornamental raised upper end, as shown, and said cap extends laterally, and within its lateral portions are formed sockets 23 for the upper ends of the 35 beams 16 and the recesses 24 at the sides of said sockets, there being as many sockets and recesses as may be required, and each socket being between two of the recesses. The sockets 23 and recesses 24 extend in 40 wardly to the central or hub portion of the cap 15, and while being of adequate depth leave a substantial body of the dome or cap within the circle of their inner ends. The sockets 23, in the construction shown, are 45 of I-shape corresponding with the I-shape of the beams 16, and the beams 16 have their upper ends bowed toward each other and are entered within said sockets, the external surfaces of the ends of said beams engaging 50 the internal surfaces of said sockets. The upper flanges 25 at the upper ends of the beams 16 engage the upper surface 26 of the sockets 23, and the edges of said flanges 25 engage the vertical surfaces 27 of the sockets 23, and the lower surfaces of said flanges 25 have a bearing upon the socket surfaces 28. The webs of the beams 16 are confined 55 between corresponding surfaces 29 of the sockets, and the flange 30 of the beams 60 which are horizontal at the dome cap, find a bearing upon the base surface 31 of the sockets 23, and the upper surface of the flanges 30 of the beams have bearings against the surfaces 32 of the sockets, while 65 the edge portions of said flange 30 engage

correspondingly formed surfaces 33 of the sockets.

The sockets 23 are spaced apart and between them are formed the recesses 24 which are of suitable dimensions to permit 70 of the riveting therethrough of the ends of the beams 16 within the sockets 23. I number the rivets 34, and these rivets extend through the side walls of the sockets 23 and through the web of the beams 16, said side 75 walls having openings in them to receive said rivets.

The recesses 24 may vary in outline, but for the purpose of avoiding undue weight of metal in the cap 15 and at the same time 80 obtaining adequate space for the convenient application of the rivets 34, I give said recesses 24 the outline illustrated in Figs. 2 and 5, the sides of the recesses conforming 85 to the sides of the sockets 23 and to the outline of the beams in cross-section.

One of the important features of my invention resides in the fact that the upper ends of the beams 16 are held within close-fitting sockets formed in the integral cap 90 and that strains either downwardly on the cap or downwardly on the upper ends of the beams 16 result in the adjacent portions of the beams having an extensive bearing surface against the inner walls of the sockets 23. The cap 15 is devoid of joints such as might be formed by fish-plates and the like, and therefore may be constructed in one piece and very efficiently receive and hold the upper ends of all of the beams 16. 100

When the cap 15 is of great weight, possibly several tons, I will make said cap in two parts, the main body of the cap being in one integral piece and the ornamental upper portion of the cap, numbered 35 in 105 Fig. 4, being in a separate piece secured by threading or otherwise to the body of the cap. I prefer to make the cap in one piece and will do so, except in case of excessive weight making it more convenient, in manufacture, to cast the cap and its superposed ornamental part in two pieces. 110

The construction shown in Figs. 1 to 6 inclusive will be fully understood without further detailed explanation. 115

The structure shown in Fig. 7 is presented to illustrate a further utility of my invention residing in the building of a dome structure which may not be pointed, as in Fig. 1, but laterally elongated. In the construction shown in Fig. 7 I illustrate one end and one middle section of a laterally elongated dome structure, the other end of the structure being omitted since it will correspond with that end thereof shown in 120 Fig. 7. In Fig. 7 the end integral dome cap, this being a modification, is numbered 36 and the integral dome cap used at the intermediate portion of the structure is numbered 37. The cap 36 corresponds with 125 130

the cap shown in Fig. 5 with the exception that its sockets 38 and recesses 39 are differently spaced from the arrangement shown in Fig. 5. In Fig. 7 the cap 36 has four 5 sockets 38 for I-beams 40 and a socket 38 for a horizontal I-beam 44, one of these sockets being at one side of the cap and the others at the transverse center and other side thereof so that the end portion of the dome structure may have four of the beams 40 extending therefrom and then downwardly. The beams 40 are secured in their sockets 38 by rivets 41, corresponding with the rivets 34 of Fig. 1.

15 The cap 37 is formed with four equally spaced sockets 42 separated by recesses 43. The individual sockets 42 correspond exactly with the individual sockets 38 and also with the sockets 23 of Fig. 5. The cap 20 37 is connected with the cap 36 by a horizontal I-beam 44, and with a similar cap by a horizontal I-beam 45, and at the opposite sides of the cap 37 said cap receives the upper ends of I-beams 46 which extend outwardly from the cap and then turn downwardly to aid in the completion of the dome structure.

25 The adjoining ends of the beams 44, 45, 46 are secured in the cap 37 by rivets 47. The caps 36, 37 are each in one integral piece, as is the cap 15, and the sockets 38, 42 in said caps 36, 37 engage the surfaces of the ends of the beams in the manner described in detail with respect to the structure shown in 30 Figs. 1 and 5.

35 In Figs. 8 and 9 I illustrate a modified construction of my invention, and therein designate the dome cap by the numeral 48. The cap 48 is in one integral casting and 40 formed with vertical sockets 49 and vertical recesses 50 between said sockets in lieu of having horizontal sockets and horizontal recesses of the character illustrated in Figs. 1 to 7 inclusive. The upper ends of the side beams 51 are curved inwardly and then upwardly, and their upper ends closely fit 45 within the sockets 49. The recesses 50 permit of the convenient application of rivets 52 for securing the upper ends of the beams 51 within the sockets 49.

50 By curving the beams 51 inwardly and then bending them upwardly, as shown in Fig. 8, said beams may be securely held within the vertical sockets 49 and when 55 therein have extended bearing surfaces against the walls of said sockets, as may be understood by reference to Fig. 9, whereby the structure may resist the varying strains which might come upon it. In other words 60 the structure shown is one of great simplicity and fewness of parts, but of great strength and durability. The cap 48 will be connected with a center rod 53 whose function will be similar to that of the rod 18 65 shown in Fig. 1.

My invention is primarily intended for the tops of domes of buildings whose frames are of structural rolled flanged beams, and in this use of the invention it will be apparent that a dome structure of very great 70 strength is secured with fewness of parts and requiring the minimum amount of labor.

What I claim as my invention and desire to secure by Letters Patent, is:

1. A dome structure of the character described comprising an integral superposed central cast cap and a series of radial rolled flanged beams extending therefrom and then downwardly on curved lines to form the skeleton of the dome, said cap having sockets receiving and conforming with the outline of the webs and flanges of said beams and in which sockets the ends of said beams are secured. 75

2. A dome structure of the character described comprising an integral superposed cast cap, a series of radial rolled flanged beams extending therefrom and then downwardly on curved lines to form the skeleton 80 of the dome, said cap having sockets receiving and conforming with the outline of the webs and flanges of said beams and also recesses intermediate said sockets, and rivets 85 extending transversely through the walls of said sockets and the webs of said beams, said recesses being of sufficient dimensions to permit therethrough the riveting of the beams 90 within said sockets. 95

3. A dome structure of the character described comprising an integral superposed 100 central cast cap, a series of radial rolled flanged beams extending laterally therefrom and then downwardly on curved lines to form the skeleton of the dome, said cap having laterally extending sockets receiving and 105 conforming with the outline of the webs and flanges of said beams and also recesses intermediate said sockets, and securing means extending transversely from said recesses 110 through the walls of said sockets and the webs of said beams. 115

4. A dome structure of the character described comprising an integral superposed cast cap, a series of rolled I-beams extending 120 therefrom and then downwardly on curved lines to form the skeleton of the dome, said cap having sockets receiving and conforming with the outline in cross-section of said beams and also recesses intermediate said sockets, and rivets extending transversely 125 through the walls of said sockets and said beams, said recesses being of sufficient dimensions to permit therethrough the riveting of the beams within said sockets. 130

5. A dome structure of the character described comprising an integral superposed central cast cap, a series of rolled beams extending therefrom and downwardly on curved lines to form the skeleton of the dome, said cap having sockets receiving and 135

conforming with the cross-sectional outline
of said beams and also recesses intermediate
said sockets, securing means extending trans-
versely through the walls of said sockets and
5 said beams, a vertical rod connected with
and extending downwardly from said cap, a
disk on said rod and radial arms extending
from said disk and secured to said beams.

Signed at New York city, in the county of
New York and State of New York, this 25th 10
day of May A. D. 1916.

THOMAS HILL.
